CLAIM

The ornamental design for a handle for taping knife with enlarged hammer end, as shown and described.

DESCRIPTION

FIG. 1 is a front view of the present handle, the rear view being identical;

FIG. 2 is a left side view of the handle of FIG. 1, the right side being identical;

FIG. 3 is a top view of the handle of FIG. 1;

FIG. 4 is a bottom view of the handle of FIG. 1; and,

FIG. 5 is top perspective view of the handle of FIG. 1.

The subject matter depicted in broken lines is not intended to be part of the claimed invention and is shown only for environment purposes.
